(57) **CLAIM**

The ornamental design for a multi-component smoking apparatus assembly as shown and described.

DESCRIPTION

FIG. 1 is a top perspective view of a multi-component smoking apparatus assembly in its fully assembled configuration;

FIG. 2 is a back view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a perspective exploded view thereof;

FIG. 9 is a perspective view of the removable sleeve of the center connector, shown separately to illustrate aspects of the design not apparent in assembled views;

FIG. 10 is a top view thereof;

FIG. 11 is a bottom view thereof;

FIG. 12 is a perspective view of the lid of the center elongated pipe, shown separately to illustrate aspects of the design not apparent in assembled views;

FIG. 13 is a perspective view of the center elongated pipe, shown separately to illustrate aspects of the design not apparent in assembled views;

FIG. 14 is a perspective view of the center connector, shown separately to illustrate aspects of the design not apparent in assembled views;

FIG. 15 is a top view thereof;

FIG. 16 is a side view of the poker, shown separately to illustrate aspects of the design not apparent in assembled views;

FIG. 17 is a perspective view of the mouthpiece, shown separately to illustrate aspects of the design not apparent in assembled views;

FIG. 18 is a perspective view of the mouthpiece stem, shown separately to illustrate aspects of the design not apparent in assembled views;

FIG. 19 is a perspective view of the bottom bowl, shown separately to illustrate aspects of the design not apparent in assembled views; and,

FIG. 20 is a perspective view of the cover of the bottom bowl, shown separately to illustrate aspects of the design not apparent in assembled views.

The broken lines shown in FIG. 8 are for purposes of annotating the exploded view only and form no part of the
